LEE S. CHADWICK, OF SHAKER HEIGHTS, AND MARC RESEK, OF CLEVELAND HEIGHTS, OHIO, ASSIGNORS TO PERFECTION STOVE COMPANY, OF CLEVELAND, OHIO, A CORPORATION OF OHIO

RETORT

Application filed March 17, 1928. Serial No. 262,580.

This invention relates, generally, to improvements in liquid fuel burners of the retort class, and more especially to improvements in the retorts or generators used in conjunction with such burners.

For illustrative purposes we have herein disclosed our invention as embodied in the type of retort used in liquid fuel cook stoves, examples of which will be found in our co-pending applications Serial Nos. 126,366 and 152,798, filed, respectively, August 2, 1926, and December 6, 1926. The present invention is applicable, however, to different types or styles of retorts so long as they are characterized by a hollow body enclosing a generating chamber and having a threaded bore leading therefrom to a gas emitting orifice, and a threaded stem operating within said bore, the stem, in most cases, carrying an axial needle for cooperation with the orifice; there being a passageway through which the gas escapes from the generating chamber along the threaded portion of the stem to the orifice.

Heretofore, with retorts of this character, spasmodic sputterings and spurtings of liquid hydrocarbon have attended their operation which interfere greatly with the action of the main burner to which gas is supplied by the retort, reducing the efficiency of said burner and causing incomplete combustion and effecting red streaks in the flame. It was discovered that this trouble occurred only under certain adjustments of the retort control stem, and upon close investigation it was ascertained that the difficulty arose when the straight passageway or channel heretofore cut or milled along the threaded portion of the stem for the passage of gas from the generating chamber to the orifice was at or near the bottom side of the bore wherein the spindle operates. Under these conditions, small bubbles or drops of the liquid hydrocarbon which reached the forward end of the generating chamber escaped through the passageway and issued from the orifice in unvaporized condition, causing the undesirable effects above described.

It is the purpose of our present invention

to obviate this difficulty by substituting for the heretofore straight, longitudinal passageway or channel in the threaded portion of the stem, a passageway of such shape, character or location as will compel the fuel expelled from the generating chamber to travel upwardly to, or rise toward, the upper portion of the bore wherein the stem operates before reaching the gas emitting orifice. It is found that this very effectively prevents liquid hydrocarbon from escaping from the generating chamber and reaching the gas emitting orifice of the retort before it is thoroughly broken up and vaporized.

An embodiment of the invention is illustrated in the accompanying drawing wherein in Fig. 1 is a fragmentary sectional elevation of a stove incorporating our improved retort; Fig. 2 is an enlarged longitudinal section through the retort; and Fig. 3 is a transverse section on the line 3—3 of Fig. 2.

The stove structure wherewith we have associated our invention for the purpose of the present disclosure includes a top 1 and a vertical panel 2, and suitably supported beneath the top 1 is a manifold 3 which has connection with a burner 4 that is situated below an opening 5 in the stove top, all of which is in accordance with common practice. Shown as formed integral with the manifold 3 is a mixer 8; and rising along the outer side of the panel 2 is a fuel supply pipe 9.

The retort, which is designated generally by the reference numeral 10, is in the form of a long tubular body that is adapted to be projected through an aperture in the panel 2 and across the burner 4 and have its discharge end extended through an opening provided for the purpose in the end wall 85 of the mixer 8.

As shown more particularly in Fig. 2, the retort comprises a tubular body 12 that is threaded at what may be considered its rear end (i. e. the end opposite its discharge end) and is screwed into the forward end of a T-shaped head 13. This head has a depending branch 14 that is connected, through a union 15, with the fuel supply pipe 9. A generating chamber 16 occupies the major portion

of the body 12, and forwardly of said chamber the body is reduced in diameter and is formed with an axial bore 17 that is internally threaded from its junction with the chamber 16 throughout a material portion of its length, as indicated at 18. The extreme forward end of said bore is also threaded for the reception of a cap 19 having a port 20 that converges forwardly adjacent its outer end where it terminates in a reduced portion 21 that constitutes the gas emitting orifice of the retort. Intermediate its threaded portions, the bore 17 is restricted by an annular wall 22, the rear face of which is beveled to constitute a valve seat 23. Within the threaded portion 18 of the bore 17 operates the threaded portion 24 of a stem 25 formed, a suitable distance forwardly of its threaded portion, to provide a valve 26 that cooperates with the seat 23, and extending axially from the forward end of said stem is a needle 27 which is adapted to enter the port 20 and, by cooperation with the tapered portion thereof and with the orifice 21, controls the passage of gas through said orifice. The valve 26 is utilized to positively shut off the flow of gas from the retort, when desired.

A spiral groove or channel 30 is milled or otherwise formed about the stem 25 in the region of its threaded portion 24 to provide a passageway for the escape of gas from the generating chamber to the gas emitting orifice 21. By so forming the passageway, the hydrocarbon is compelled to rise a material distance above the bottom portion of the bore wherein the stem operates and in so doing any which may escape from the generating chamber in liquid condition is broken up and thoroughly vaporized.

Where the stem 25 extends outwardly through the rear end of the head 13, the joint between the stem and head is closed by the usual packing gland 32; and the stem 45 is equipped beyond the head with an operating handle 33.

Having thus described our invention, what we claim is:

1. A retort comprising a substantially horizontally disposed, elongated hollow body enclosing a generating chamber and having a threaded bore leading therefrom, and a stem having a threaded portion operating within said bore, there being a passageway between opposed surfaces of the stem and body that leads past the threaded portion of the stem and extends diagonally of the threads and at least a part of which passageway is at all times a material distance above the bottom of the bore irrespective of the adjustment of the stem.

2. A retort comprising a substantially horizontally disposed, elongated hollow body enclosing a generating chamber and having a threaded bore leading therefrom, and a

stem having a threaded portion operating within said bore, there being a passageway between opposed surfaces of the stem and body that leads past the threaded portion of the stem and extends diagonally of the threads and is inclined with respect to the axis of the bore. 70

3. A retort comprising a substantially horizontally disposed, elongated hollow body enclosing a generating chamber and having a threaded bore leading therefrom, and a stem having a threaded portion operating within said bore, there being a spiral passageway between opposed surfaces of the stem and body that leads past the threaded portion of the stem and is of considerably greater pitch than the threads. 75

4. A retort comprising a substantially horizontally disposed, elongated hollow body enclosing a generating chamber and having a threaded bore leading therefrom, and a stem having a threaded portion operating within said bore, the stem having a groove in its threaded portion that is inclined to its axis and cuts diagonally through the threads. 80

5. A retort comprising a substantially horizontally disposed, elongated hollow body enclosing a generating chamber and having a threaded bore leading therefrom, and a stem having a threaded portion operating within said bore, the stem having a spiral groove about its threaded portion that is of considerably greater pitch than the threads. 85

In testimony whereof, we hereunto affix our signatures.

LEE S. CHADWICK.
